FILLING MOTION FOR SHUTTLELESS LOOMS

Edward J. Berry, Cranston, and George T. Allen-
son, Lincoln, R. I., assignors to Draper Corpora-
tion, Hopedale, Mass., a corporation of
Maine

Application December 16, 1949, Serial No. 133,338

26 Claims. (Cl. 139—127)

1

The present invention relates to filling motions for shuttleless looms, and more specifically, to filling motions of a type adapted to control yarn fed from an external source to be taken by filling inserting devices such as are employed with looms of the type to which reference is made.

It is a general object of the invention to devise a filling motion which shall comprise a compact and unitary subassembly, and which shall function effectively to feed filling from an external source of supply to rapidly operated filling inserting devices functioning to insert filling in pairs of connected picks, each pick of which is held in a separate shed.

A more specific object of the invention is that of providing a filling handling mechanism driven in synchronism with other parts of the loom and which is especially designed to present the filling to an inserting means in a reversed relationship at alternating picks thereby to assure that each pick is inserted in as nearly as is possible the same general manner and under the same physical conditions and influences.

It is another object of the invention to provide a filling motion as just above described which shall control the relationship of the filling at succeeding picks so as to maintain the loose or released end of the filling at the same side, preferably beneath, the inserting means at each pick.

Another object of the invention is that of providing a filling cutting and clamping means adapted to function beneath and very close to the inserting means and which is operated in a very simple and effective manner for exploring and engaging the filling for withdrawing it out of the range of inserting means and for severing and releasing one end while clamping and retaining the other cut end.

It is a further object of the invention to provide a filling manipulating injector adapted normally to maintain the filling out of the path of the inserting means, but to present it in the path of that means at appropriate times, and in combination therewith, a thread return guide adapted to cooperate with the injecting device for confining the filling in such manner that it is always properly engaged at appropriate times as the injecting means functions, and also, for releasing or freeing the filling from the injecting means at proper intervals during the filling inserting cycle.

Other objects will be apparent from the following more detailed disclosure.

In shuttleless looms and especially in looms of that type in which filling is taken from an ex-

2

ternal source of supply and is inserted in a warp shed by rapidly reciprocating devices of a type well known in the prior art, it is essential that the filling be handled or guided in such manner as to present it at appropriate times and in a particular relationship so that it may be faithfully and correctly engaged by the inserting means. It is also necessary to release a free end of that filling at a time when an amount thereof has been drawn sufficient for reaching across the entire extent of the warp shed and slightly beyond, and also to clamp or bind the filling so that no further quantity thereof shall be drawn from the source of supply until another pick is to be inserted. One very common form of weaving on these looms involves the insertion of a pick from one side of the loom, then after changing the shed, insertion of a second pick from the same side maintaining continuity of filling between the two picks thereby to provide for a selvage at that side of the fabric. While it is quite possible to insert filling in these looms and from an external source of supply according to other methods, the description hereinafter to be given will refer particularly to insertion from a single side of the loom and to the production of fabric wherein the filling takes the form of repeated pairs of connected picks or "hairpins" as just described.

Duplication of the mechanism at each side of the loom makes it quite possible to insert filling from both sides and to produce a selvage at each side, although that involves added mechanism. The advantage of a selvage formed by the loops between adjacent connected picks is to be desired, but that is to an extent counteracted by other disadvantages with which we are not especially concerned at this point. It should suffice to say that the invention may be practiced at a single side or at both sides and the mechanism, as will be well understood by those conversant with this art, merely involves duplication and in some instances, reversal of the shape of the parts and positioning thereof since the operation is to be performed at the opposite side and in a reverse direction. If the filling is inserted entirely from one side, a selvage may be produced at the opposite side by locking the projecting ends with twisted selvage threads, or in any other satisfactory way.

The invention comprises a complete unit mounted adjacent the end of and at the front of a loom of the type described and which preferably is driven from some part of the loom which is moving synchronously with the filling inserting means, lay, and other parts. The device itself

is largely encased within a suitable closure, but that is not entirely essential although preferable. The filling itself may be supported adjacent the end of the loom and in proximity to the filling motion and, as herein illustrated, is provided in the form of relatively large thread packages from which it may be drawn over the end of the package and through suitable tension means to be guided more or less in a direction parallel to the direction of movement of the inserting means as it projects into the warp shed. Preferably, the entire filling handling mechanism is confined within a relatively small space, that is, insofar as the actual filling engaging and manipulating devices are concerned, and is positioned very close to the edge of the fabric being woven and therefore very close to the point at which the filling inserting means actually enters the filling into the shed.

The filling handling means includes a binder or clamp member hereinafter termed an outer clamp and through which the filling is guided just before being threaded through and engaged between restraining means at opposed ends of a filling injecting means which is especially provided for a complex movement incidental to the presentation of the filling to the carrier in reversed relationship at succeeding picks. The injecting means has in cooperation therewith a filling return guide which has the dual function of confining the direction of movement of filling at certain times so that it may be engaged properly between restraining means at the injector, and at other times, functions in cooperation with the movement of the injector, to strip the filling therefrom at an appropriate time during the cycle of operation.

At a point just to the outside of the edge of the fabric, a combined thread clamp and cutter, hereinafter referred to as the inner clamp and cutter, is adapted to move to different positions during the cycle in one of which it extends beneath the filling inserting means and between that means and the filling, to explore for and catch the filling whereupon it may be withdrawn to cut the filling at an appropriate instant and to clamp it preparatory to repeating the insertion cycle. This inner clamp is also moved throughout a relatively small extent for releasing the filling at an earlier part of the cycle.

The individual instrumentalities just above enumerated are controlled by independent governing devices which, however, are all operated and driven in timed relationship to other movements of the loom and which are adapted to bring about the separate movements of the parts in accordance with the requirements thereof during the weaving of two picks of filling, or the completion of a single cycle. While other actuating means may be employed, it is preferred to use a plurality of cams, these all being mounted upon a single shaft driven positively from some appropriate movement at the loom, and in some instances, positively moved follower and lever devices actuated by the cams and interconnected to the separate instrumentalities, and in other instances, single cams providing a movement of the parts in one direction while the return movement is provided by some convenient means such as a spring or the like.

The invention will hereinafter be described in greater detail by reference to one specific embodiment thereof as illustrated in the accompanying figures of drawing wherein:

Fig. 1 is a perspective view showing a shuttle-

less loom to which the invention has been applied, the general outward appearance and characteristics of the filling mechanism, its drive means, and the manner in which the supply of filling is supported adjacent thereto.

Fig. 2 is an end elevation of a part of the loom and of the filling motion and further illustrating the drive therefor.

Fig. 3 is a perspective view taken at the right hand end of the loom and from the rear thereof showing the filling handling instrumentalities and the general arrangement of parts shown in Fig. 1, but as seen from the opposite direction.

Fig. 4 is a transverse section taken through the filling motion and showing the operating parts most of which are enclosed within the casing.

Fig. 5 is a vertical section taken at line 5—5, Fig. 4.

Fig. 6 is a vertical section taken at line 6—6, Fig. 4.

Fig. 7 is a similar section taken at line 7—7, Fig. 4.

Fig. 8 is a corresponding vertical section taken at the line 8—8, Fig. 4.

Fig. 9 is a detail perspective view showing the inner binder and cutter completely opened for exploring for the thread or filling.

Fig. 10 is a similar view, but showing the inner binder closed.

Fig. 11 is a top perspective of the same parts showing the clamp and cutter during the process of closing for cutting and clamping the filling.

Fig. 11a is a detail of part of the mechanism of Figs. 9, 10 and 11, but showing a modification thereof.

Fig. 12 is a section taken through a part of the loom to which the filling motion has been applied and illustrating certain modifications of parts thereat which cooperate with the filling motion.

Fig. 13 is a perspective view showing to an enlarged scale those parts of the filling motion which engage and manipulate the filling as the carrier is taking the thread on the first pick of a cycle of inserting two complete, connected picks.

Fig. 14 is a similar perspective view showing taking of the filling at the second pick.

Fig. 15 is a similar view but illustrating insertion of the second pick at a slightly more advanced stage at which time the filling is about to slip from one of the nibs on the injector.

Fig. 16 shows a still later point in the cycle at which time the filling is being explored preparatory to cutting and clamping it at about the end of the insertion of the second pick.

Fig. 17 shows the position the parts occupy after cutting and clamping at the final stages of inserting the second pick, this being the position the parts occupy preparatory to the start of a cycle.

Figs. 18 and 19 are plan and elevational views, respectively, of the cam which provides movements for the inner clamp and cutter.

Figs. 20 and 21 are corresponding views of the cam which controls the outer clamp.

Figs. 22 and 23 show cooperating, complementary cams which govern the axial movement for the filling injector.

Figs. 24 and 25 are corresponding views of similar cooperating cams devised to provide the rotary or oscillatory movement for the injector.

Figs. 26-39 are diagrammatic views illustrating the position and functioning of the various filling controlling instrumentalities at different points during the complete cycle of inserting two connected picks.

Fig. 40 is a view showing a small section of fabric woven according to the method employed.

Now referring to Figs. 1, 2 and 3, the general organization of a shuttleless loom to which the invention has been applied will be described. The loom comprises, among other parts, loomsides 50 and 51, a plurality of girts 52, and other structural parts including a breast beam 53 which go to make up a conventional loom framework. The warp threads are supported at the back of the frame and pass through the usual warp stop motion devices and are then threaded through heddles in heddle frames such as the frame 54 hung upon a top motion including the suspending straps 55, 56 passing over sheaves 57, 58 rotatable on brackets carried by an arch 59. Springs enclosed within a casing 60 bias the parts just described in such manner as to draw the heddle frames upwardly while cams at the lower part of the loom structure function upon treadles to pull downwardly upon other parts of the harness mechanism, only some of which show in Fig. 1, but which need not be described here since they are conventional and their actual construction and mode of operation are well understood by those skilled in this art.

The warp threads after passing through the heddles are threaded through a reed 61 carried between a lay beam 62 and a hand rail 63, Fig. 12, after which the warp passes to the fell of the fabric and the fabric then passes onwardly to the take-up mechanism such as the usual sand roll or other equivalent devices, and to a cloth roll upon which it is wound and by means of which it may be taken from the loom when a sufficient quantity of material has been finished. The mechanism incidental to take-up of the fabric and winding on the said roll is shown in part in Fig. 1, but need not be described in detail as it is not different from that employed in conventional looms.

As illustrated in detail in Fig. 12, and as shown to some extent in Fig. 1, the lay beam 62 is carried adjacent the upper ends of swords 64, extensions of those swords in an upward direction being employed for fixing the hand rail in position. The swords attach in an adjustable fashion at their lower ends to brackets or levers 65 which are pivoted on a rock shaft 66. By means of cams 67 and 68 rotatable with a cam shaft 69, the lay mechanism is swung to and fro in properly timed relationship. The cams 67 and 68 function upon followers 70 and 71 carried at the end of arms, one of which is integral with the bracket 65 and the other of which is pivoted thereto at 72 and pressed by means of a spring 73 in such direction that the followers always bear tightly against their cams. The cams themselves provide for a dwell period of 180°, more or less, and that dwell period serves to hold the lay structure in stationary position while the filling is inserted. During the active part of the cycle the cams move the swords and lay structure forwardly to effect beating up of the last laid pick of filling.

The filling is inserted by carrier devices mounted at the ends of flexible tapes, one at each end of the loom, and in Fig. 3, one such tape is illustrated at 74, it being understood that these tapes tend to maintain a rectilinear form, but are flexible enough to be wound upon the tape wheels 75 as they are withdrawn from the shed and outwardly beyond the filling motion. These tape wheels are of relatively light construction and are mounted on pivots 76 carried in supports at

the outer portions extending frame structures which include the horizontally disposed members 71 and the more or less vertically disposed parts 78. This framework is attached to the loomsides 5 and the entire structure ties together to make a relatively rigid supporting means for the tape wheels which are oscillated to and fro under the influence of certain intermeshing gears, shafts and reciprocating racks, the latter being reciprocated by cranks or eccentrics, or in any other satisfactory manner all as described in United States Patent 2,604,123. The manner of reciprocating these tapes or of imparting movement to other similar filling inserting means which may 10 form the basis of a loom structure to which the invention is applied differs according to the prior art, and it is not deemed necessary to go into detail concerning that part of the basic loom mechanism since the invention may be utilized to 15 advantage with many looms of the same type.

The entire loom is driven by a motor or from any other convenient source of power and that power is preferably conveyed through clutch means and the loom is to be started and stopped 20 by engaging or disengaging the clutch, and preferably, at the same time, by releasing and applying a brake as is frequently done in looms of all types so as to effect stopping as rapidly as possible for reasons well known to those skilled 25 in the art.

The tape wheels are preferably shielded by casings 79 in which are carried at angularly spaced points antifriction rollers for facilitating movement of the tape as it is wound upon the wheel 35 75 or unwound therefrom. The tape passes through straight guideways 80 just prior to its entry into the shed within which it inserts filling.

The invention as herein illustrated is applied to a shuttleless loom wherein the filling is inserted 40 at one side only. That may be altered so that filling is inserted at each side in which event, the actual construction of the filling carriers attached at the ends of the flexible tapes would vary. In the latter instance, such carriers might 45 preferably take the form illustrated in the co-pending application above mentioned. Where filling is inserted from one side only, one of the carriers as illustrated in Fig. 13 and also in the diagrammatic views, comprises a boxlike, sheet metal structure 81 tapering downwardly to merge smoothly into the tape 74 and being more or less pointed as at 82 for passing through the shed more smoothly. The opposite or front face of the carrier is similarly pointed and at the top and lower portions of the boxlike structure, notches 50 83 provide for receiving the filling and for maintaining it centrally of the carrier as the latter pushes the filling inwardly to a point somewhere near the center of the shed or of the fabric being 55 woven. The action of the carrier in thus protecting the filling inwardly to approximately the center of the shed is such that a doubled length of filling is pushed inwardly, one end of that filling 60 extending back to the supply and the other being held for a length of time until sufficient material has been projected inwardly so that one end may be released or cut and thereafter no further filling drawn from the supply. One end of the said doubled length of filling extends from 65 the top notch 83 while the other end will extend from the corresponding lower notch and along the bottom of the carrier and beneath a portion of the tape. The actual manner in which the tapes are disposed with respect to the lay and 70 the manner in which the filling is controlled by 75

the tapes to tension it is described in the patent above-mentioned and need not be described in greater detail here.

The opposite carrier member comprises a hook and trap structure as illustrated in the diagrammatic figures and that hook and trap serve to engage the filling at transfer and extend it over the rest of the shed. It should suffice to state here that the carrier at the left hand side of the machine according to the specific illustration here given engages that short stretch of filling between the top notch 83 and the notch directly below at the lower part of the carrier and having engaged it and effected transfer from the carrier 81 to the opposite or hooked carrier 84, Fig. 29, carried by a tape 85 corresponding to tape 14 the action of the latter carrier simply results in drawing out the filling which has been measured off and inserted as a doubled length so that the released or cut end thereof is extended across the shed to the opposite side of the fabric and for a very short extent beyond for the purpose of effecting the formation of some type of selvage as above indicated.

The supply of filling is preferably mounted adjacent the filling motion itself, but may be carried at any convenient locality at that end of the machine. Here the filling in the form of supplies S is mounted upon spindles such as the spindle 86 carried at the upper end of bracket 87 fixed on a platform 88 mounted at the end of the loom framework as shown. The supplies are preferably arranged in duplicate with the trailing end of one being attached to the leading end of the other so that when the first becomes exhausted, the loom may continue to draw filling from the other so that there will never be a point at which the loom must stop due to exhaustion of filling.

The filling indicated by F is drawn axially from the package and passes through an aperture or eyelet 89 in a shield 90 which to some extent controls ballooning of the filling and separates the supplies from the filling motion, that shield 90 being removed in Fig. 3 so that parts which would otherwise be hidden are exposed to view.

The filling motion itself, indicated generally by a numeral 91, is to a great extent enclosed within a casing 92 having a cover 93 which rocks about a hinge pin 94 so as to tip back and expose those parts within the casing. This entire filling motion is devised as a unitary structure and is mounted upon a bracket 95 supported on the machine framework and preferably adjustable thereon so as to position the unit by moving it through a limited extent. The interior of the casing as well as the actual parts which control the filling itself are collectively shown in Fig. 4. All of the instrumentalities are cam controlled, these cams being supported upon a shaft 96 carried in bearings 97 and 98, herein shown as antifriction type bearings, although it is to be understood that other bearings may be employed if desired. The casing may be oil tight at its lower part, at least, and thus the internal parts lubricated by dipping in oil in a reservoir provided by the lower part of the casing, or each part may be separately or otherwise lubricated.

The shaft 96 as illustrated in Figs. 2 and 4, is driven through spiral gears 99 and 100, the former being fixed at the upper end of a more or less vertically disposed drive shaft 101. The gear 100 is fixed at the end of shaft 96 and both of these gears are enclosed within casing member 102 which is bolted to or otherwise attached to the side of the main casing 92.

The upper end of shaft 101 is carried in a bearing 103 bolted to the side of casing 92 while the lower end of that shaft is borne within a corresponding bearing 104 which forms a part of a bracket 105 bolted to the loomside 50 and adjustable thereon for positioning the parts and assuring proper intermeshing of the various gears.

Shaft 101 is driven from the main cam shaft 69 through gears 106 and 107, the latter being mounted upon a short spindle 108 carried in bearings 109 also forming a part of bracket 105 and this gear 107 also drives a bevel gear 110 which in turn meshes with and drives a corresponding gear 111 fixed at one end of a shaft 112, the other end of that shaft having keyed or otherwise fixed thereto a corresponding gear 113 meshing with a gear 114 at the lower end of shaft 101. The shaft 112 is rotatable within the bearings 115 and 116 depending from the bracket 105. Thus, rotation of cam shaft 69 as the loom is operated, through the train of gears just described, drives the cam shaft 96 within the casing or housing 92, that shaft being driven at one-half the speed of cam shaft 69 so that each of the cams carried by the shaft 96 makes one complete revolution for every two picks inserted, that is, for each complete cycle of inserting a so-called "hairpin" or pair of connected picks.

The following description devoted to the outer binder or clamp, the injector, the filling return guide, and the inner clamp and cutter will be taken up in the order stated, each of the said mechanisms being described in detail along with the details of that part of the operating mechanism which governs its movements.

The filling F after being drawn through the eyelet 89 or corresponding guide means and after being drawn from the supply, may pass through tensioning means (not shown), but which may take any convenient form desired. For example, disk tensions may be employed and the tension to be imposed upon the filling by such devices may be adjusted in accordance with the material itself and with other factors. If desired, other devices adapted to prevent knotting or formation of slubs or collection of lint upon the filling and possibly causing undesired effects may be employed if desired.

The outer clamp shown in Figs. 4, 5 and 13 comprises a relatively fixed and a movable member, the relatively fixed portion of the clamp being constituted as a pad 117 at the lower end of the depending arm 118, the latter being comprised as a part of a complete bracket 119 bolted or otherwise attached to an upper, flattened portion of an extending hub or boss 120 formed as an integral or other part of the casing 92. So that the filling may be maintained in alignment with the center of the clamp a pair of guides 121 and 122 are adjustably attached by means of screws passing through slots and into a widened part of the bracket 119. Apertures in these guides permit the filling to pass between and more or less centrally of the fixed pad 117 and the cooperating movable clamp member 123 which is formed at the end of a plunger or axially movable rod 124 guided within suitable bearings in the hub or boss 120. A spring 125 bearing against a shoulder on the plunger 124 and against a cooperating shoulder within the hub 120 is under sufficient compression for forcing the plunger and thus the movable portion of the clamp outwardly against the fixed pad 117 with a force appropriate for maintaining the thread or filling in clamped engagement in the event the clamping action is in

effect, but permitting movement of the plunger 124 inwardly of the casing 92 at such times as a cam 126 carried by shaft 96 affects a follower 127 at the upper crooked end 128 of a two armed lever pivoted at 129, the lower end 130 of which is forked to engage a collar 131 at the inner end of the plunger.

The cam 126, as illustrated in Figs. 4, 5 and 20 and 21, is mounted upon a hub 132 which is pushed over a cylindrical portion and also against a conical portion of the shaft 96 and held in place by a nut 133. The cam is comprised of two portions, one disk portion which extends throughout 360° and a filler or adjustable part 134 which is attached to the disk by bolts 135 and 136 passing through an elongated slot and adjustable throughout an angular extent so as to vary the position of rise for the follower 127 or the time of releasing the filling by varying the relative angular position of the point of the cam 137. The clamp is closed as the follower 127 drops from the point 138. By loosening the nut 133, Fig. 4, and moving the entire cam 126 on the shaft, this point of drop-off is capable of being varied, thereby to time the termination of drawing filling from the supply, and therewith, the length of material going into the first pick. As the follower drops from the point 138, the spring 125 is permitted to close the clamp, and when it rises upon point 137, the plunger is withdrawn against the tension of spring 125 and the clamp is opened. The clamp must be opened prior to the start of drawing filling from the supply for the second pick.

Now referring to Figs. 4, 6, 7 and 13 in particular, the injector the purpose of which is to position the filling in front of or in the path of the carrier 81 will be described in detail. The injector itself comprises opposed arms 139 and 140, Fig. 4, which actually are formed as a U-shaped thread controlling and guiding means pivoted to be turned about an axis along which it may also move axially. These arms 139 and 140 are adjustably positioned but fixed to one end of the spindle 141 which is rotatable in bushings or other bearings in a hub or boss 142, Fig. 7, projecting from the casing 92, and also in a bearing 143 intermediate the casing. The arm 140 has an aperture 144, Fig. 13, through which the filling is threaded and the opposite arm 139 has two nibs 145 and 146 which are formed with a slight incline at their inner surfaces so that the thread may slip therefrom when desired. These nibs may also be bent away from the center of the pivot as illustrated in Fig. 4.

The filling threaded through aperture 144 may not escape therefrom, but it is only at such times as the filling injecting means is positioned parallelly with the direction of movement of the carrier that the nibs may engage at either side of that filling. After the filling has been thus trapped between the nibs 145 and 146 while the arms are horizontally disposed and with the aid of other mechanism hereinafter to be described, that filling is injected into the path of the carrier by pushing the injector arms toward the path of the carrier or away from the casing 92 toward the back of the loom. At the same time the injector is oscillated or rotated throughout about 90° from horizontal position to a more or less vertical position thereby to position the stretch of filling extending from the aperture 144 to one of the nibs 145 or 146 across the pathway of the carrier. As will hereinafter be described, the rotation throughout approximately 90° occurs first in one direction for one pick and then in the

other direction for the next succeeding pick for a purpose hereinafter more definitely explained.

The mechanism for moving the injector toward the path of the carrier 81 will first be described. The central or largest portion of shaft 96 has keyed thereto a hub 147 to which are attached cams 148 and 149. These cams shown more clearly in Figs. 7, 22 and 23, are complementary and may be adjusted as a unit about the shaft, but are locked thereto when the proper position has been once determined.

These cams function upon followers 150 and 151. The followers 150 and 151 are positioned in offset relationship, one to one side and the other to the other side, of the two armed lever pivoted at 129 having an upwardly directed arm 152 and a depending arm 153 the lower end of which is forked at 154 to engage between collars 155 fixed on shaft or spindle 141 and thus, by rotating these cams as the shaft 96 is rotated, the arm 153 is rocked to and fro in properly timed relationship to project the injector inwardly and to withdraw it in properly timed relationship to the movements of the filling carrier 81.

The rocking or oscillating movement imparted to the injector is derived from the complementary cams 156 and 157 which are also mounted for rotation with the shaft 96, these cams being bolted to the hub 158 which is in turn keyed to the shaft as illustrated in Fig. 4 and acts to impart movement to a bell crank lever having arms 159 and 160, as seen in Fig. 6, and a hub portion pivoted on a stub shaft 161 bolted to the side of the casing 92. Followers 162 and 163 mounted for rotation upon opposite sides of the general center line of the lever impart movement from the cams 156 and 157 to the bell crank lever, the swinging movements of that lever being carried through to rock a cross shaft 164 mounted in bearings 165 and 166, Fig. 4, cast integrally or otherwise formed as a part of the casing 92.

A pinion 167, Fig. 6, is keyed or otherwise fixed to the shaft 164 between the two bearings just above mentioned. The arm 160 of the bell crank lever is formed at its free end as illustrated in Fig. 6 to provide a sector 168 having teeth cut therein for meshing with the pinion 167. Thus, rocking movement of the bell crank lever causes a rotation of the shaft 164 first in one direction and then the other and the ratio of the effective moment arms of these parts and the amount of angular movement imparted to the bell crank lever causes approximately a 90° rotation of this shaft at each oscillation thereof.

Now referring to Fig. 4 and also to Fig. 7, the spindle 141 to which the injector is attached through the coupling hub 169 is adapted to be turned on its axis independently of its movement along or axial of that axis by a bevel gear 170 which is splined internally to engage corresponding splines 171 at that end of the spindle. The hub 172 of the gear is spaced from the intermediate bearing 143 by a washer 173 and from an opposed guide and thrust member 174 by a sleeve 175. An extension 176 of reduced diameter is guided within a bushing 177 carried within the guide and thrust member 174 which extends outwardly of the casing 92 being bolted thereto in any suitable manner and having a part 178 extending far enough to permit the extreme axial movement of the reduced end 176 of the spindle.

A corresponding gear 179 is keyed to the adjacent end of shaft 164 and meshes with gear 170 so that the rocking movement imparted to the cross shaft is conveyed to the spindle 141 through

the splines which interconnect the hub of the gear and that spindle.

Again referring to Figs. 6, 24 and 25, the complementary cams 156 and 157 are adjustable as a unit upon the shaft and are provided with double the number of lobes to be found on the cams 148 and 149 since at each time the injector is moved to present the filling to the carrier 81, it must be rocked first in a counterclockwise direction for pick #1 of a connected pair of picks of filling and then returned, and for pick #2 of the pair, must be rocked in the opposite direction and returned while, of course, the axial movement is merely duplicated on that second pick.

Now referring to Figs. 4, 8, 9, 10, 11, 11a and 16, the inner clamp and cutter will be described. That thread manipulating and controlling instrumentality includes a relatively fixed clamp element 180 which has a leather or fibre facing 181 and which is disposed at the end of a plunger 182 which extends back to a boss or support 183 cast integrally or otherwise formed as a part of the casing 92. While this part of the clamp is referred to as the relatively stationary clamp member, it is to be understood that it has a slight resiliently opposed movement back into the support 183 and the term applied to it is used merely by way of distinguishing between it and the other portion of the clamp and of the cutter which is actually moved positively by mechanism hereinafter to be described throughout a considerable extent for the purpose of effecting the release, clamping and cutting of the filling. The movement of clamp 180 and plunger 182 to which it is attached is for the purpose of providing a resilient pressure between the pad 181 and the complementary clamping surface of the movable clamp 184 which is shown opened in Fig. 9 and closed at Fig. 10.

Plunger 182, as shown in Fig. 4, moves back into the support 183 against a spring 185 and the tension on this latter spring is just sufficient to press the pad 181 against the surface of movable plunger element 184 with the required amount of force necessary for holding the thread. A forked extension comprising the arms 186 and 187 engageable at either side of a short projection 188 having a flattened portion 189 shouldered at either end prevents rotation of the clamp and also limits movements thereof outwardly under the influence of the spring 185. It is to be noted that as illustrated in Figs. 4 and 10, engagement of the movable clamp with the pad 181 merely results in compressing spring 185 very slightly and the arms 186 and 187 actually move very little at that time, the movement being just sufficient to insure contact without controlling the movement of the clamp member 184 with extreme precision and prevents any possible release of the filling due to vibration or the like.

The movable clamp member 184 is attached at the end of a cutter bar 190 which slides in the support 183 and is so formed at its lower side as to provide a cutter or shear member 191 which is hooked or inclined in such direction as to catch the filling and to draw it back during the return movement of the cutter and clamp to sever or shear it against the sharp edge of a spring blade 192 better illustrated in Fig. 11. The end or nose portion of the clamp and cutter just described is bevelled at the lower surface and is pointed as at 193 for the purpose of slipping over the filling at the time the cutter functions to engage and sever and clamp it, thereby serving to engage above it and to cam it downwardly dur-

ing an exploring stroke to the position illustrated in Fig. 16. It is to be understood that at that time the cutter moves outwardly beneath the tape 14 there being a very slight clearance between the top surface of the cutter bar and the lower surface of the tape. The filling is then more or less underneath the tape or just to one side thereof and is separated from the tape as it angles downwardly from the carrier at the end of the tape so that there is always ample room for the point of the cutter to engage between the tape and the filling. Continued movement of the cutter to the positions of Figs. 9 and 16 engages the shear 191 over the filling so that return movement thereof to the position of Fig. 10 must cut the filling and also clamp it between the members 181 and 184. The shearing action actually takes place a brief interval before the clamping according to the preferred timing as is customary in instruments of this sort.

As shown in Figs. 9, 10 and 11, a curved extension 194 notched as at 195 for reception of the filling tends to maintain that filling in proper position with respect to the cutter element 191 and is positioned slightly nearer the casing 92 than the point 193 of the cutter member so as to keep the filling away from the blade 191 until contact is actually made with the spring blade 192. This added part may be used although it is not necessary with some types of filling, but has been found to be useful in some instances where the filling has tended to become frayed as it has been drawn past the blade 191.

According to the modification of Fig. 11a, a guide 196 having a smaller notch 197 expressly for the purpose of preventing erratic travel of the filling is provided. This notched guide may likewise keep the filling away from the cutter blade, but its main purpose is to guide the filling and prevent it from flying about during the cutting cycle.

Now referring specifically to Figs. 4 and 8, the means for operating the inner clamp and cutter includes a cam 198 fixed to a hub 199 which is mounted on the shaft 96 and retained in place and in a properly adjusted position by means of the nut 200. This cam will be described in greater detail in a later paragraph. It functions upon followers 201 and 202 mounted at opposite sides of the general center line of a two armed lever comprising the arms 203 and 204 pivoted at 205 and connected at its lower forked end 206 by a suitable pin 207 engageable within a notch or other indentation in an operating rod 208 slidably in bearings in the casing, one bearing 209 adjacent the front part thereof and the second bearing 210 adjacent the opposite side of the casing.

This operating rod 208 carries at the end adjacent the clamp and cutter and outside the bearing 209 a depending connector element 211 having passed therethrough a projecting stud or pin 212 which extends through a slot 213 in the casing extension or support 183 and into a cooperating aperture in the cutter bar 190. Movements of the operating rod 208 are imparted thereby to the cutter bar and thus the clamp may be closed and the cutter operated to sever and to retain the severed end of filling running back to the supply, or by other movements derived from the cam the clamp may be opened slightly thereby to release the held end, or the entire movable portion of the clamp and cutter extended rearwardly of the loom a considerable distance as illustrated in Fig. 16, to explore and

catch the filling preparatory to drawing it back toward the closed portion of the instrument for cutting.

A spring 214 normally under considerable compression pushes the rod 208 in a direction to open the clamp and cutter while a second spring 215 enclosed within an extending housing 216 bolted or otherwise attached to the front face of the casing 52 serves to act as a buffer spring being compressed between the collar or shoulder 217 on a plunger 218 which in turn extends through to contact the reduced extending end of rod 208 carried within the bearing 210.

The cam 198 which controls the movements of the inner clamp and cutter is for the most part one which acts to impart movement in a single direction through the follower 201, but which does act at one point in the cycle through the other follower 202, as a complementary cam for positively actuating the cutter. The main disk portion of the cam extending for 360° of arc is supplemented by a second part 219, Figs. 18 and 19, which is bolted to the main disk. The latter partial disk or sector is adjustable throughout an extent so as to vary the position of the point 220 which determines the release of the held end during the insertion of the first pick and therefore the length of the first pick. Setting of this point is necessary to assure that the pick will extend clear across the fabric and beyond the extreme edge just far enough to serve in the production of a selvage.

The continued movement of the cams in the direction indicated by the arrow causes the follower 201 to move into the depression between the points 221 and 222 at which time the cutter makes its extreme movement for the purpose of exploring the filling and catching it preparatory to terminating the length of the second pick by cutting, the position of the point 222 being adjusted by movement of the entire cam as the parts are originally assembled for establishing that particular point in the cycle. The spring 214 is under considerable compression and assists in moving the parts outwardly to their extreme position, but since there is considerable inertia and since the parts are to be moved with great speed, a short cam 223 bolted to a sector 224 likewise adjustable angularly about the main cam disk, serves to impart a positive movement at that time as it engages follower 202 and the pathways provided by cam 223 and that of the depression between the points 221 and 222 are substantially complementary. Sector 224 is also shaped to provide the cam point 221 and a concentric part in extension of the periphery of the main disk 198. Adjustment of the sector correspondingly moves point 221 and the point of cam 223. After the exploration for the filling and cutting and clamping thereof, the parts remain in closed position until the point 220 is again reached at which time the cycle is repeated.

Now referring to Figs. 4, 13, 15, 16 and 17, a filling return guide mounted at the end of a supporting arm 225 comprises the arms 226 and 227 which converge to a V-shaped somewhat pointed thread controlling notch having a lowermost shelf or horizontal portion 228, the purpose of which is to restrain the filling so that it will align with the space between the nibs 145 and 146 at the injector. Fig. 17 shows the parts in that particular relationship at the termination of the second pick or start of the first pick since the injector and the position of the filling be-

tween the clamp and supply does not change during that interval.

At the start of the second pick the thread extends from the selvage and at the fell over the top of the cutter mechanism, but is still restrained within the notch or V portion and held upon the ledge or shelf 228 so that it is likewise properly disposed between the nibs 145 and 146 before the injector moves outwardly and rotates for presenting that filling to the carrier.

This thread return guide has another function, namely, that of stripping the filling from the nibs as the injector is returned after the filling has been taken by the carrier. The movement 15 of the injector back from presenting the thread to the carrier and the return rotation thereof wipes the filling against either the upper or lower converging surface within the guide and that, in combination with the tension in the 20 filling, results in a rapid stripping of the loop from the nibs 145 or 146, as the case may be.

For the first pick of a cycle the filling is desirably stripped or released from its nib as quickly as possible. The angle of the filling holding 25 surfaces and action of the injector are combined with a wiping action of the edge of the lower arm 227 to accomplish that. At the second pick it is desired to hold the filling at the then acting nib as long as practicable, or at least, long enough 30 to permit the cutter to enter between the tape and filling. For that purpose the outer surface of the nib 146, Fig. 15, is notched slightly to hold the thread until a safe point of release has been reached.

35 The lower arm of the guide extends forwardly to an enlarged end 229, Figs. 13 and 17, upon which is adjustably mounted a bearing block 230 formed from fibre or other wear-resistant, but more or less frictionless material against the 40 top surface of which the tape 74 is guided or borne during reciprocating movement thereof. The block is adjustable being held in position by bolts 231 which pass through oversized openings in the end 229 of the arm or in some other 45 way to permit a small amount of movement thereby to position the top surface of the block initially for proper operation of the parts, or to reposition it later in the event that becomes necessary or desirable.

50 In Fig. 12 one of the swords 64 is shown and brief mention has heretofore been made of that part and the general arrangement of elements operated thereby. The sword is of special form adapted to cooperate with the filling motion as 55 the latter is positioned extremely close to the edge of the warp threads into which the filling is inserted, that being something not possible of obtainment with the usual sword employed on conventional looms or on other shuttleless looms 60 heretofore known. Beginning just above the level of the top edge of the lay beam 62, the sword is curved rearwardly of the loom as at 232 and is then carried forwardly to a connecting pad 233 for the hand rail 63. This leaves 65 between the hand rail and top of the lay a space 234 which is adapted to receive or permit the operation of the filling motion parts or thread handling instrumentalities such as the filling return guide and the inner clamp and cutter, especially when the latter extends forwardly for exploring the filling. Only the sword at the side at which the filling motion is positioned need be constructed in this manner, but, of course, if filling is inserted from both sides of the loom, 70 both swords are correspondingly shaped.

15
Operation

Now having described the details of a preferred embodiment of the invention as illustrated in the accompanying figures of the drawing, the operation of the mechanism will be reviewed, more particular reference being made to Figs. 13-17 and 26-39.

As shown in Fig. 26 which represents the position of the various parts intimately involved in the introduction and insertion of filling, the particular position indicated there being termed the 0° position for the cam shaft at which time the cycle may be considered to commence. The filling is at that point threaded through or controlled by the various devices including the outer clamp which is not closed at that time, the injector, the filling return guide and the inner clamp which is closed and which holds the cut end of filling left at the termination of the previous pick or cycle. At that particular point, the injector has actually been moved inwardly slightly and has been rotated counterclockwise (as seen from the front of the loom). The carrier 81 is then withdrawn to its outermost position.

Continued operation of the loom causes that carrier to be projected inwardly toward the filling as the tape 74 is pushed inwardly by the tape actuating or driving means and, as illustrated in Fig. 27, the 50° position, the notch 83 has just engaged the filling which at that time, as illustrated in Fig. 13, is maintained in a somewhat vertical direction by means of the injector pushed inwardly to its fullest extent and rotated to substantially a vertical position. The nib 145 holds a loop of the filling which extends from the inner clamp, about that nib and then up through the eyelet 144 and back through the outer clamp to the supply.

Further movement of the parts as indicated in Fig. 28 causes the filling to be drawn from the supply and extended in the form of a doubled length of material since the cut end is still retained by the inner clamp. This figure is taken at about the 73° position at which time the filling and the carrier have actually entered the warp shed and also at which time the loop of filling held by nib 145, Fig. 13, has been released. As before explained, it is desirable on the first pick of a cycle to release the filling from that nib as quickly as is practicable. While some variation in the actual timing incidental to that function is possible, the release must be accomplished fairly soon after the filling has been taken by the carrier to avoid possibility of the released loop engaging undesirably with some part of the mechanism, for example, looping beneath the inner cutter rather than passing above as intended. If that should happen, the pick would be measured longer than intended.

The action continues to the position of Fig. 29, the 142° position where the inner binder is opened very slightly thereby to release the end of the filling since at that time, sufficient thread will have been measured to extend to the other side of the fabric and to provide a proper amount thereof for forming a selvage as heretofore explained. It is also apparent that the drawing of the filling from the supply is no longer necessary and in the following figure, Fig. 30, about 3° further advanced in the cycle, the outer binder has closed to hold the yarn against further withdrawal from that source. The timing of parts at this critical point is such that the outer

5 binder does not hold the filling against withdrawal before it has been released by the inner binder. While about 3° of movement is one which serves satisfactorily, it is quite evident that some variation is possible.

10 It is to be borne in mind that the actual control of the elements being described at this point is derived from the various cams illustrated in Figs. 18-25 and that those cams are actually 15 rotating at one-half the angular speed of the main cam shaft and therefore, will make a complete revolution for every two revolutions of the main cam shaft or a complete revolution for every two picks of filling inserted. The closing 20 of the outer binder just above mentioned occurs due to the dropping of the follower from the cam point 128, Fig. 20, that point being adjustable to time the function properly. Likewise, the length of pick #1 is also governed by the dropping 25 of the appropriate follower from point 220 on the cam illustrated in Fig. 18, that bringing about slight opening of the inner binder. Of course, the cams shown in Figs. 22-25 control the movements of the injector which incidentally has been returned practically to its innermost, horizontal, inactive position at 145° of cam shaft travel.

30 As shown in Fig. 31, the carrier 81 continues on toward the center of the fabric where transfer is effected as the carrier 84 engages and traps the thread or filling pushed into the shed by the first carrier and draws it outwardly to the position shown in Fig. 32. The shed, of course, changes at an appropriate time just before or just about at the withdrawal of carrier 84 from the edge of the fabric and the pick is beaten into the fabric all in a manner understood by those familiar with this art. The carriers continue on outwardly returning toward their initial position, Fig. 32 showing them at their 305° 35 position at which the outer clamp has again opened so as to permit the drawing of filling from the supply when that becomes necessary. At that time the filling is extending from the fell of the fabric and back to the supply being threaded through the eyelet in the injector and guided in the notch of the return guide, but not being particularly restrained by any other elements at that time. In Fig. 33, the 335° position, the tape driving means and the carriers are moving back to occupy practically the same position they did at the 0° position of Fig. 26. The start of inserting the second pick then commences shortly after the 345° position of Fig. 34. The carrier 81 then moves inwardly while the injector as controlled by the cams which govern it, is moving rearwardly and has engaged the filling between the nibs 145 and 146 and is just starting its rotation in a clockwise direction.

40 Now referring to Fig. 35, the 55° position at the second rotation of the main drive or cam shaft, or the second pick of the cycle, the filling is being taken by the carrier, but it is to be noted that at this time that filling extends from the fell, back over nib 148, and down through eyelet 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 and to be moved rearwardly for exploring the filling which is at that time below the tape. The loop of filling extending from the carrier notch to the nib 146 is still retained by the nib being held in place by the small notch heretofore mentioned and shown in Figs. 14 and 15.

Continuation of the cycle to a position for the crank shaft of about 110° or more continues at which time the loop may be released from that nib as the injector is withdrawn and also rotated slightly about its axis, the thread being stripped from the nib by the under side of the top arm 226 of the filling return guide. The 125° position is shown in Fig. 37 at which time the cutter and binder having explored and engaged the filling as illustrated in Fig. 16 are returning to their closed position, and also at which time the loop of material released from the nib 146 has almost been drawn into the selvage, that point being reached very shortly thereafter and before the 175° position of Fig. 38 at which time the cutter and the inner clamp have closed thereby severing and retaining the end of the filling extending from the supply. At that time the proper amount of material has been measured to reach clear across the fabric and continued movement of the parts results in transfer and extension of the filling to the other side of the fabric after which it is beaten in and the parts returned to their initial or zero position as shown in Fig. 39, that position corresponding to the position of Fig. 26 at which point the cycle may again be repeated.

The movement of the cutter and inner clamp as just described is controlled by the cam illustrated in Figs. 18 and 19 and this description of operation as related to the diagrammatic figures is also so tied up with the previous description of the mechanism itself that the operation of the various parts including the cams will be clear.

In Fig. 40 a small section of fabric has been illustrated and it can be seen there that the filling is inserted in the form of "hairpins" or spaced pairs of picks interconnected by a selvage loop. Since the insertion is entirely from one and the same side, all of these loops are at the side of the fabric at which the filling motion is disposed and the other side of the fabric is characterized by projecting selvage threads which may be interlocked by any form of selvage such, for example, as the well known twisted selvage capable of being controlled by various mechanisms well known to those skilled in the art.

The example of operation just given relates to the settings peculiar to one particular form the invention may take. Of course, the values may well vary for other machines and change to an appreciable extent for the weaving of fabrics of different widths and for different speeds of operation.

The term "reversed" has been used to describe the effect produced upon the filling by the injector. The reversal or change in the relationship of the filling which is presented to and taken by the carrier is actually employed in sustaining a general condition so that it remains constant. The reversal of a small stretch of filling thus results in establishing at each pick, a condition under which the released end of filling is always disposed or caused to be drawn at the same side of the inserting means (here the lower side of the carrier and its tape).

While one embodiment of the invention has

been disclosed, it is to be understood that the inventive concept may be carried out in a number of ways. The invention is, therefore, not to be limited to the precise details described, but is intended to embrace all variations and modifications thereof falling within the spirit of the invention and the scope of the claims.

We claim:

1. In a filling motion for shuttleless looms having filling inserting means which draw and insert filling from an external source of supply, the combination of an outer filling clamping means and an inner filling clamping means through which the filling is guided, and an injecting means between said outer and inner clamping means for engaging the filling and presenting it in the path of the inserting means.
2. In a filling motion for shuttleless looms having filling inserting means which draw and insert filling from an external source of supply, the combination of an outer filling clamping means and an inner filling clamping means through which the filling is guided, and an injecting means between said outer and inner clamping means for engaging the filling and presenting it in the path of the inserting means, and means for reversing the relative position of the injecting means at alternate picks thereby to prevent the filling to the inserting means in reversed relationship.
3. In a filling motion for shuttleless looms having filling inserting means which draw and insert filling from an external source of supply, the combination of a filling clamping means and a cooperating guide means for maintaining said filling in alignment with the direction of movement of said inserting means and out of the pathway thereof, and an injecting means between said clamping and guide means and means for moving said injecting means to a position for presenting the filling in the pathway of the inserting means and for reversing its direction of movement at succeeding picks thereby to cause the filling to be taken in a reversed relationship at alternate picks.
4. In a filling motion for shuttleless looms having filling inserting means which draw and insert filling from an external source of supply, the combination of a filling clamping means and a cooperating guide means for maintaining said filling in alignment with the direction of movement of said inserting means and out of the pathway thereof, and an injecting means between said clamping and guide means comprising a U-shaped, two-armed member, a spindle to which said member is fixed and bearings within which said spindle is free to move axially and to oscillate to and fro throughout a predetermined angular extent, a filling guiding eyelet adjacent the end of one of said arms of said U-shaped member and filling engaging and restraining nibs projecting from the opposite arm, said injecting means being movable for presenting the filling in the pathway of the inserting means as the said U-shaped member is moved axially toward the inserting means and is oscillated for the required angular extent to present the filling across the path of said inserting means, and control means for said injecting means for reversing the direction of its oscillation at succeeding picks thereby to cause the filling to be taken in a reversed relationship at alternate picks.
5. In a filling motion for shuttleless looms having filling inserting means which draw and insert filling from an external source of supply, the

combination of an outer filling clamping means, an inner filling clamping means, a thread return guide means, and an injecting means between said outer and inner clamping means, said clamping means, injector and the filling restraining portion of said thread return guide means being disposed in substantial alignment and out of the pathway of the inserting means, and means for projecting said injecting means into the pathway of said inserting means and for oscillating it to a position to present the filling in the path of the inserting means.

6. In a filling motion for shuttleless looms having filling inserting means which draw and insert filling from an external source of supply, the combination of an outer filling clamping means, an inner filling clamping means, and a thread return guide having convergent arms adapted to engage the filling and between which it is restrained, and a U-shaped filling injecting member comprising two oppositely directed arms one said arm being provided with an eyelet through which the filling is threaded, the opposite arm having spaced nibs by which the filling is guided, said outer and inner clamping means, thread return guide and said injector being so disposed as to maintain the thread out of the pathway of the inserting means when the injector is withdrawn, and means for projecting said injector inwardly into the path of the inserting means and for oscillating it so that the said arms are disposed one above and one beneath the inserting means thereby to present the filling in the path of the inserting means.

7. In a filling motion for shuttleless looms having filling inserting means which draw and insert filling from an external source of supply, the combination of an outer filling clamping means, an inner filling clamping means, and a thread return guide having convergent arms adapted to engage the filling and between which it is restrained and a U-shaped filling injecting member comprising two oppositely directed arms one said arm being provided with an eyelet through which the filling is threaded, the opposite arm having spaced nibs by which the filling is guided, said outer and inner clamping means, thread return guide and said injector being so disposed as to maintain the thread out of the pathway of the inserting means when the injector is withdrawn, and means for projecting said injector inwardly into the path of the inserting means and for oscillating it so that the said arms are disposed one above and one beneath the inserting means thereby to present the filling in the path of the inserting means, said means for projecting said injecting means inwardly to present the filling in the path of the inserting means further being movable in opposite directions at succeeding picks thereby to reverse the relationship of the filling as it is taken by the inserting means and to assure that the released end of the filling shall always be disposed at the lower side of the said inserting means.

8. In a filling motion for shuttleless looms having filling inserting means which draw and insert filling from an external source of supply, the combination of a filling clamping means and a cooperating, convergent, thread confining guide means for maintaining said filling in alignment with the direction of movement of said inserting means and out of the pathway thereof, and an injecting means between said clamping and guide means for engaging the filling and deflecting its pathway so that it is disposed substantial-

ly normal to the path of the inserting means and into the path thereof.

9. In a filling motion for shuttleless looms, a filling injector and cooperating filling guiding means, said injector comprising filling engaging arms, a spindle to which said arms are fixed and bearing means upon which said spindle and arms are mounted for rotation and within which they may be moved axially, and filling confining means at the ends of said arms, said guide means comprising convergent means positioned to limit the movement of the filling so that it is engaged by said confining means.

10. In a filling motion for shuttleless looms, a filling injector and cooperating filling guiding means, said injector comprising filling engaging arms, one said arm having an aperture therein through which the filling is threaded, and the opposite said arm having at its end spaced, angularly divergent nibs between which the filling is releasably restrained, a spindle to which said arms are fixed and bearing means upon which said spindle and arms are mounted for rotation and within which they may be moved axially, said guide means comprising convergent means positioned to limit the movement of the filling so that it is engaged by said nibs.

11. In a filling motion for shuttleless looms, a filling inserter, a filling injector and cooperating filling guiding means, said injector comprising filling engaging arms, a spindle to which said arms are fixed and bearing means upon which said spindle and arms are mounted for rotation and within which they may be moved axially, and filling confining means at the ends of said arms, said guide means comprising convergent arms positioned to limit the movement of the filling so that it is restrained and thereby caused to align with the filling confining means at the said arms, one of said convergent means having adjacent the end thereof an adjustably positioned bearing member for the said filling inserter.

12. In a filling motion for shuttleless looms, a filling injector and cooperating filling guiding means, said injector comprising a U-shaped member, a spindle to which said member is fixed and bearing means upon which said spindle and member are mounted, means to move said spindle and member axially of their bearings and to oscillate them therein, filling confining means comprising an eyelet at the free end of one arm of said U-shaped member and spaced nibs at the corresponding end of the other arm of that member, said guide means comprising convergent means positioned to limit the movement of the filling so that it is engaged between said nibs.

13. In a filling motion for shuttleless looms, a filling injector which comprises a U-shaped member, a bearing means upon which said member is mounted and means to move said member axially of the bearing means and to oscillate it therein, and filling confining means comprising an eyelet at the end of one arm of said U-shaped member and spaced nibs at the corresponding end of the other arm of the member.

14. In a filling motion for shuttleless looms, a filling injector which comprises a U-shaped member, a bearing means upon which said member is mounted and means to move said member axially of the bearing and to oscillate it therein, and filling confining means comprising an eyelet at the end of one arm of said U-shaped member and spaced nibs at the corresponding end of the other arm of the member, said nibs being angled divergently at the surfaces at which the

filling is releasably retained so that it may slip therefrom at a predetermined point during the cycle of movement.

15. In a filling motion for shuttleless looms, a filling injector which comprises a U-shaped member, a bearing means upon which said member is mounted and means to move said member axially of the bearing and to oscillate it therein, and filling confining means comprising an eyelet at the end of one arm of said U-shaped member and spaced nibs at the corresponding end of the other arm of the member, at least one of said nibs having a notch cut transversely thereof and within which the filling is restrained until forcibly stripped from the nib.

16. In a filling motion for shuttleless looms, a filling injector and operating means therefor comprising a bearing means, a shaft axially slideable and oscillatable in said bearing means, a two armed member fixed to one end of said shaft and having adjacent the extremity of one arm an aperture through which the filling is threaded, and at the extremity of the opposite arm, spaced nibs for guiding and retaining the filling so that it shall be releasably constrained to extend in the direction of said arms, and means to move said shaft axially and to oscillate it first in one direction and then in the opposite direction for reversely presenting the filling to an inserting means at alternate picks.

17. In a filling motion for shuttleless looms, a filling injector and operating means therefor comprising a bearing means, a shaft axially slideable and oscillatable in said bearing means, a two armed member fixed to one end of said shaft and having adjacent the extremity of one arm an aperture through which the filling is threaded, and at the extremity of the opposite arm, spaced nibs for guiding and retaining the filling so that it shall be releasably constrained to extend in the direction of said arms, and means to move said shaft axially comprising cam means, a follower for said cam means and interconnecting means by which the movements imparted to the follower by said cam are conveyed to the said shaft, and means to oscillate the shaft first in one direction and then in the opposite direction for reversely presenting the filling to an inserting means at alternate picks, said means comprising a cam means and a follower deriving movements from said cam means, interconnecting linkage for imparting the movements of the follower as governed by the cam to the said shaft which comprises gears one of which is mounted upon said shaft and which is splined thereto so that the shaft may move axially of the gear while being driven thereby.

18. In a filling motion for shuttleless looms, a filling injector and operating means therefor comprising a bearing means, a shaft axially slideable and oscillatable in said bearing means, a two armed member fixed to one end of said shaft and having adjacent the extremity of one arm an aperture through which the filling is threaded, and at the extremity of the opposite arm, spaced nibs for guiding and restraining the filling so that it shall be releasably constrained to extend in the direction of said arms, and means to move said shaft axially which comprises complementary cams, a lever pivoted adjacent said cams and having followers, one for each cam, and a forked end of said lever engageable between restraining means on the shaft thereby to impart swinging movements of the lever to the shaft, and means for oscillating the

shaft first in one direction and then in the opposite direction for reversely presenting the filling to an inserting means at alternate picks comprising complementary cam means, a lever pivoted adjacent said cam means and having followers, one engageable with one said cam means and the other engageable with the other, a sector having gear teeth cut therein at the end of said lever opposite the follower, a cross shaft, a gear fixed to one end of said cross shaft and meshing with the teeth of said sector, bevel gears, one at the other end of said cross shaft and one on the said shaft to which the two armed member is fixed, said gears being in intermeshing engagement and the latter having a splined connection to the said shaft so that it may drive it and also permit axial movement of the shaft relatively thereto.

19. In a filling motion for shuttleless looms, a filling injector and operating means therefor comprising a pivot means, a shaft axially slideable and oscillatable in said pivot means, a two armed member fixed to one end of said shaft and having adjacent the extremity of one arm an aperture through which the filling is threaded, and at the extremity of the opposite arm, spaced nibs for guiding and retaining the filling so that it shall be releasably constrained to extend in the direction of said arms, said nibs having filling restraining surfaces inclined at an angle such that the filling when engaged and projected into the warp shed, is held by a nib for a short interval until the angular relationship of the filling to the nib is altered to cause it to slip off, and means to move said shaft axially and to oscillate it first in one direction and then in the opposite direction for reversely presenting the filling to an inserting means at alternate picks.

20. In a filling motion for shuttleless looms, the combination of a filling injector and a thread return guide in cooperation therewith, means upon which said injector is axially movable and oscillatable, said injector comprising a two armed member having adjacent the extremity of one arm an aperture through which the filling is to be threaded, and at the extremity of the opposite arm, spaced nibs for releasably retaining the filling, said thread return guide comprising convergent arms and being so positioned that when the injector is oscillated to a position out of alignment with the general direction of travel of the filling and is moved in a direction parallel to and toward the direction of convergence of the arms, the filling is stripped from the nib.

21. In a filling motion for shuttleless looms, the combination of a filling injector and a thread return guide in cooperation therewith, means upon which said injector is axially movable and oscillatable, said injector comprising a two armed member having adjacent the ends of each arm means for guiding the filling in the general direction of said arms, the filling guiding means at one said arm being adapted for releasably restraining the filling, said thread return guide comprising convergent arms and being so positioned that when the injector is oscillated to a position out of alignment with the general direction of travel of the filling and of the inserting means, it is axially moved in a direction parallel to and toward the direction of convergence of the arms, the filling is then stripped from said releasable means.

22. In a filling motion for shuttleless looms

having filling inserting means which draw and insert filling from an external source of supply, said inserting means functioning to draw a doubled length of filling from the source, one stretch of which extends beneath the inserting means, and a clamp and cutter means normally maintained out of the path of said inserting means and filling, but movable to a position beneath the said inserting means and between the inserting means and the filling for engaging the filling and severing and clamping it upon retraction to initial position.

23. In a filling motion for shuttleless looms having filling inserting means which draw and insert filling from an external source of supply, said inserting means functioning to draw a doubled length of filling from the source, one stretch of which extends beneath the inserting means, a cutter normally maintained out of the path of said inserting means and filling, and means for moving said cutter to a position between the said inserting means and the filling for engaging the filling and withdrawing it outwardly from the path of the inserting means and for severing it.

24. A thread clamp and cutter for looms of the type described comprising a fixed cutter blade and a relatively fixed clamping pad, a movable member carrying a complementary clamping pad and a cooperating cutter member and means to move said movable member to three different positions, in one of which the said clamping pads are pressed together and the blades engaged for severing the filling, in a second of which the pads are separated slightly to release filling, and to a third position where the member is engaged over the filling to draw it against the fixed blade and to clamp it upon retraction.

25. A thread clamp and cutter for looms of the type described comprising a fixed cutter blade and a relatively fixed clamping pad, a movable member carrying a complementary clamping pad and a cooperating cutter member said movable member having its end portion beveled to a substantially pointed edge to facilitate its projection between the filling carrier and filling.

26. A thread clamp and cutter for looms of the type described comprising a fixed cutter blade and a relatively fixed clamping pad, a movable member carrying a complementary clamping pad and a cooperating cutter member and means to extend said movable member for engaging the filling to be clamped and cut, and a notched guide forming a part of said relatively movable member for guiding the filling to maintain it in alignment with its intended path through the clamp and cutter.

EDWARD J. BERRY,
GEORGE T. ALLENSON.
